CLAIM

The ornamental design for an adjustable ball and clevis mount assembly, as shown and described.

DESCRIPTION

FIG. 1 is a perspective view of an adjustable ball and clevis mount assembly showing our new design;

FIG. 2 is a first side view of FIG. 1 thereof;

FIG. 3 is a second side view of FIG. 1 thereof;

FIG. 4 is a front side view of FIG. 1 thereof;

FIG. 5 is a rear side view of FIG. 1 thereof;

FIG. 6 is a top view of FIG. 1 thereof; and,

FIG. 7 is a bottom view of FIG. 1 thereof.

The broken lines in the figures are included for the purpose of illustrating portions of an adjustable ball and clevis mount assembly and form no part of the claimed design.
